UNITED STATES PATENT OFFICE.

HERMAN HOLLERITH, OF GARRETT PARK, MARYLAND, ASSIGNOR TO THE TABULATING MACHINE COMPANY, A CORPORATION OF NEW JERSEY.

APPARATUS FOR USE IN TABULATING SYSTEMS.

1,030,305.

Specification of Letters Patent. Patented June 25, 1912.

Application filed July 27, 1906. Serial No. 328,076.

To all whom it may concern:

Be it known that I, HERMAN HOLLERITH, a citizen of the United States, residing at Garrett Park, Montgomery county, Maryland, have invented certain new and useful Improvements in Apparatus for Use in Tabulating Systems, of which the following is a full, clear, and exact description, reference being had to the accompanying drawings, forming part of this specification.

This invention relates to the Hollerith tabulating system, a distinguishing feature of which is the employment of a record-card having index-points, such as punched holes, which are located on each record in predetermined positions and in accordance with the data which each record-card represents.

The object of my present invention, of which I have shown a preferred form in the drawings, is primarily to provide means and apparatus for use in the tabulation of population statistics where each individual represents an item or unit to be counted in accordance with the particular characteristics of the individual, such as race, nativity, sex, occupation, age, etc. In the compilation of statistics, the characteristics according to which the individuals or items are counted or the records tabulated may be as comprehensive as the predetermined plan of compilation may require, but for the purpose of avoiding unnecessary prolixity of description I have illustrated and will describe my invention as it would be employed in counting individuals according to the following characteristics, to wit: white native males; white native females; white foreign males; colored males and colored females.

I will also describe my invention as employed in classifying or sorting the records according to their characteristics and in selecting or rejecting the records according to the further characteristics of age and sex. This simple plan or scheme of tabulation will suffice to make my present invention clearly understood, but may be elaborated to any desired extent as previously explained and it is not my intention to limit my invention to the tabulation of population statistics.

In the accompanying drawings Figure 1 shows, diagrammatically, a portion of a typical but not an essential form of tabulat-

ing apparatus embodying my invention; Fig. 2 shows, diagrammatically another portion thereof; Fig. 3 shows a record-card in simplified form; Fig. 4 shows apparatus for classifying or sorting the record-cards, the sorting devices being shown in elevation; Fig. 5 is a detail elevation of the sorting guide actuators on a larger scale; Fig. 6 is a plan view of the sorting mechanism; Fig. 7 is a modification of the apparatus illustrated in Fig. 1; Figs. 8 and 9 are diagrams illustrating means for classifying the records or rejecting records upon which the data or characteristics are unusual or inconsistent so that they may be readily noted or compared with the original records for correction if necessary. Fig. 10 is a view in elevation of one form of apparatus embodying my invention and Fig. 11 is a partial plan view thereof on the line 11-11 (Fig. 10), showing the conducting blades 28 and 29 in a different position.

Similar reference characters are employed to designate like parts in all the views.

Each index-point position of a column represents a different characteristic of the individuals to be counted, and in practice provision should be made for a more elaborate recording of these characteristics, but in the simple example which I shall first employ in describing the operation of my invention, only six of these index-point positions are assumed to be utilized to wit: the four index-point positions in the left hand column marked *a*, *n*, *c*, and *w*, representing foreign born, native born, colored and white respectively and the two index-point positions of the middle column, representing females and males respectively. In the particular record-card shown in Fig. 3, the index-points are shown as formed in the positions marked *n* and *w* in the left hand column, and in the position marked *f* in the middle column, the record thus representing a native, white female. The index-points are usually and preferably formed by punching holes at the proper index-point positions.

Referring to Fig. 1, a number of the record-cards 1 are placed on edge, similarly positioned on a platform 2 and are fed one by one, by means of a reciprocating feed knife carried by a cross-head 3, feed rollers

4, rotating conducting drum 5, past record-controlled circuit controlling devices which in the form of apparatus shown are conducting brushes 6 and 7, each of which 5 forms one terminal of an electric circuit. The ends of the brushes are slightly resilient and rest normally on the conducting surface of the drum 5 which by means of a brush 8 is connected with the opposite terminal of a circuit. The cross-head 3 is reciprocated by a crank-disk 9 with which it is connected by the connecting-rod 10. The crank-disk is constantly driven in synchronism with the feed rollers, drum and other 10 parts of the apparatus to be described, by a suitable motor 11. The brushes 6 and 7 are insulated from each other and are so located that the end of the brush 6 traverses the index-point positions of the left hand 15 column on the record-cards, and the brush 7 traverses the positions of the middle column as the cards are fed past them. Only two of these circuit controlling devices are illustrated, but it will be understood that 20 there should be one for each operative column of index-point positions, and each one of the circuit-controlling devices is common to a column of index-point positions, which expression I employ to briefly denote the 25 fact that each of the said circuit-controlling devices is adapted to be actuated to open or close an electrical circuit by an index-point punched at any index-point position in its column. A cam 14 constantly driven by 30 the motor 11 in synchronism with the feeding apparatus is arranged to actuate the contacts 15 to open and hold open the circuit from the battery 16 during the intervals between the moving cards, but permits the 35 contacts to close the circuit just as the edge of an advancing card passes between the brushes 6 and 7 and the drum 5, the contacts remaining closed until just as the card is about to pass from under the brushes, 40 when the cam 14 again opens the contacts 45. When the advancing edge of a record-card passes between the drum and the brushes it carries the ends of the brushes out of contact with the drum, but when an 50 index-point or punched hole reaches a brush the latter will contact with the drum through the hole momentarily while the hole passes under the brush.

The specific object of my present invention 55 is the operation of a tabulating device, which term I employ, in a measure arbitrarily, to designate the counters or registers shown in Fig. 2, the sorting guides shown in Fig. 4 or the selecting devices shown in 60 Figs. 8 and 9, all of which will be more fully described hereinafter.

In the particular form of apparatus embodying my invention shown in the drawings the operation of each of these tabulating 65 devices is controlled by an electro-mag-

net controlled by a record-controlled device common to a plurality of index-point positions each representing a different characteristic of the item or unit, and means are employed for actuating or controlling the 70 action of each of these tabulating devices only through the medium of its appropriate index-point or points, comprising a commutating device consisting of a number of sections or rings 18, 19, one for each of the 75 circuit-closing brushes. Each section of the commutating device consists of a conducting segment 20 and a plurality of conducting contacts 22, one for each index-point position of the record-card, separated by suitable 80 non-conducting material 23.

Although for the sake of clearness I have shown the sections or rings 18 and 19 as arranged in different axial planes, they are to be mounted in a fixed position in axial alignment concentrically with the shaft 25, and are separated sufficiently from each other to permit the operation of conducting blades 28 and 29 which are mounted on the rotating shaft 25, driven by the motor 11, in synchronism with the card feeding means, so that one arm of the switch blades will traverse all the conducting contacts 22 of its section as the index-point positions of each record-card pass under the brushes, that is to say when the index-point positions at the bottom of the columns are under the brushes one end of the switch blades 28 and 29 will be in contact with the first or top 90 conducting contacts of all the sections while the other ends of the blades will be in contact with the conducting segments and will conductively connect the top contact points with the segments in all the sections, and as the card passes down, the contact points will be successively connected with the segments as the successive index-point positions pass the brushes. The top and bottom non-conducting segments 23 (Fig. 1) are longer 95 than the non-conducting sections of the commutator rings which separate the conducting contacts 22 from each other and are so proportioned that the switch blades will be in contact with them during the intervals between the cards or rather between the last index-point position of one card and the first index-point position of the succeeding card. The switch blades 28 and 29 are 100 preferably slightly resilient so as to furnish an efficient wiping contact as they traverse the conducting elements of the commutator sections. Each of the brushes or record-controlled contacts 6 and 7 is conductively connected with the conductor plate of its 105 corresponding commutator section. The form of this commutating device is not material since any circuit controlling mechanism by which the operating magnets or 110 their equivalents may be connected with the brush when the corresponding index-point 115 120 125 130

or points coöperate therewith, will answer the same purpose.

In the form of apparatus which I have shown two electric circuits are employed, 5 one to actuate the relay magnets shown in Fig. 1, and which I have designated generally by the character 40, and the other of which is controlled by the relay contacts to actuate the electro-magnet or magnets which operate or control the operation of the tabulating devices, and which I have designated generally by the character 41. For the sake of clearness I have illustrated these as independent circuits and in separate diagrams, 10 the complete circuit 40 which actuates the relay magnets being shown in Fig. 1, while the complete circuit or circuits 41 which actuates the magnets of the tabulating device are shown in Fig. 2. The terminals of the circuit 41 are indicated as connected to the relay contacts in Fig. 1, and the terminals of the circuit 40 are similarly shown as connected to the relay magnets in Fig. 2. But in this connection, I desire to state, that 15 wide variations may be made in the arrangement of circuits and connections, and that mechanically operating devices may be employed in carrying out my invention, as, for instance, by the substitution of mechanically operating devices for the relay magnets employed to hold the circuits under control as will be presently described. These and other modifications within the scope and spirit of my invention will however naturally occur to those skilled in the art and for this reason I deem it inadvisable to set forth in the proper limits of this specification such possible modifications in detail since they involve no departure from my invention.

40 Referring to Fig. 1 of the drawings, each of the operative contact points 22 of the commutator sections is connected with the coils of one of the electro-magnets 50—55 provided with relay contacts, which as the 45 contacts are placed in series with the magnet coils when the magnet is actuated, I term series relay magnets. Each of the magnets 50—55 is connected with one or more relay magnets 56—65, it being understood that in this particular form of apparatus there will be one series relay and one or more relay magnets for each index-point position utilized in the scheme of tabulation employed.

55 The relay contacts of the magnets 56—65 are actuated to control the counter circuits 41, one or more of them being arranged in series with each of the magnets 70—75 which actuate the registering counters 60 77—82 shown in Fig. 2.

From the foregoing description it will be understood that in the particular form of apparatus illustrated in Fig. 1, when considered as under the control of a record-card 65 having its index-points located as indicated

in Fig. 3 and representing a native, white female, the index-point positions at the bottom of the columns come under the brushes as the card is fed downward, the switch-blades of the commutator will be in contact 70 at one end with their conducting strips 20 and at the other with the top contact points 22 of their respective commutator sections. As the bottom hole *w*, representing "white" is punched in the left hand column, when 75 this index-point comes under the brush 6 the latter will contact with the drum 5 and close a circuit through the switch blade 28, top contact point 22 of the section 18, the coils of the series relay magnet 50 and relay 80 magnet 56 to the other side of the line, energizing the magnets 50 and 56 (see also Fig. 2) and closing the relay contacts of those magnets. As soon as the contacts of magnet 50 are closed a circuit will be closed through 85 the conductor 42, which also includes the coils of the magnets, and the relay contacts will be held closed notwithstanding that the circuit from the brush is broken as soon as the index-point *w* passes the brush. As the 90 record-card passes downward the brush 7 will contact with the drum 5 through the index-point *f*, representing "female" in the middle column closing a circuit through the switch blade 29, the second contact point in 95 the commutator section 19, series relay contacts of the magnet 55 and the relay contacts of magnets 63, 64 and 65. The index-point *n*, representing "native" in the left hand column will when it reaches its operative position under the brush 6, in the manner before explained close the series relay contacts of the magnet 52 and the contacts of the magnet 58. As this particular record 100 under consideration has only these three index-points no further action of the magnets will occur during the downward passage of the card until the top index-point positions have passed under the brush. When the card reaches this position a circuit controlling device, comprising a cam 85, which is driven by the motor in synchronism with the moving card, and contacts 86, is arranged to close the circuit 41 momentarily, and as the relay contacts of the magnets 56, 110 58 and 63 which are all connected in series with the magnet 71, are still held closed by the series relay magnets 50, 52 and 55, a circuit will be completed through these contacts and through the magnet 71, imparting 115 one impulse to the counter 78 and registering on its dial one unit having the characteristics native, white, female in accordance with the record on the card. The cam 14 thereupon, and just before the record-card 120 passes the brushes, actuates the contacts 15 to break the circuit 41, 42 and the armatures all of the magnets are released, the circuit being held open by the cam 14 until the edge of the next card passes under the 125 130

brushes. It will be noted that although the circuits through the other counters are closed at one or more of the relay contacts, yet only the one counter will be operated by this record because one or more of the contacts in the other counter circuits remain open.

It will be apparent that the independent circuit controlling device in the circuit 41 is, theoretically, not essential since the closing of the circuit may be effected by the closing of the last relay contact to be actuated, but I prefer to close this circuit by contacts actuated independently of the record and accessibly located, to avoid deterioration of the relay contacts by sparking.

The closing of the circuit 41 by the contacts 86 will also energize a magnet 87 and release a latch lever 88 which is fixed to a deflector 89, pivoted in a chute 90, arranged below the ejector rollers 4*. The chute 90 is divided by a longitudinal partition into two compartments 91, 92. When the latch lever 88 is released by the movement of the armature of the magnet 87 a spring 93 will throw the deflector 89 across the compartment 92 before the card reaches the chute, and the card will be guided into the compartment 91 and will be deposited in a suitable receptacle. But if the record be defective or not properly punched, as for instance, if neither the position *m* or *f* should be punched in the record under consideration, the counter circuit would remain open at the corresponding relay contacts and the magnet 87 would remain inactive. The deflector would not be actuated and the record would be guided into the compartment 92 and conducted to a different receptacle or position, the operative cards thus being grouped separately from such cards as may be inoperative through defective punching or otherwise. A cam 94 arranged to revolve in synchronism with the motor resets the latch lever and deflector after the card enters the chute.

In the foregoing description I have referred more particularly to the diagrammatic views, (Figs. 1 and 3). In order to illustrate more clearly the arrangement and synchronous movement of the various parts and the manner of making the connections to the electrical devices in the circuit, I have, in Figs. 10 and 11, illustrated one form of apparatus adapted to carry out my invention. In these views, A represents the side plates of the machine connected by the transverse bars *a*. The conducting drum 5, (which is here shown as engaging with the upper feed rollers 4 to effect the feeding of the cards), is journaled in the frames A and a driving pulley B is mounted on the shaft of the drum. The pulley B is connected by a belt with the motor 11, (Fig. 1). The crank disks 9, (to which the connecting rods

10 on each side of the machine are connected), are mounted integrally with gears E on the shaft *e*, and are formed with gear teeth which mesh with gears *c*, mounted integrally with the gears C on the shaft carrying the feed rollers 4 (Fig. 11). The gears C mesh with the gears D on the shaft of the conducting drum 5 upon which the driving pulley B is mounted. The gear *c* shown in Fig. 10 is partly broken away to show the brush 7.

Transmission gears F, mounted on the shaft *f*, are by gears G and H, connected to drive the ejector rollers 4*, shown in dotted lines, (Fig. 10). The gears F also mesh with gears J on the shaft *j*. The cam 94, by which the deflector latch lever 88 is reset, is also mounted on the shaft *j*. The cam 14 which controls the contacts 15 in the circuit 40 is mounted on the shaft *f*. A gear K is mounted on the shaft *k* at one side of the machine and meshes with the gear L on one end of the shaft 25, upon which the switch blades 28 and 29 are secured and from which they are insulated by the non-conducting bushing *l*. The commutator sections or rings 18 and 19 are mounted rigidly, and concentrically with the shaft 25, on cross-bars M extending between the plates A of the machine. The cam 85 which controls the contacts 86 in the circuit 41, is mounted in the shaft *k*.

The brushes 6 and 7 are connected with the conducting segments 20 of their respective commutating sections 18 and 19 by means of conducting wires O provided with ordinary plug connectors *o*, and the conducting contacts 22 of the sections 18 and 19 may be connected to their respective magnet circuits, (shown in Fig. 1), through the medium of a switch-board P of ordinary construction, but, as will be understood, the switch-board is not an essential feature of my invention, since in practice, the magnet circuits may and often would be directly or otherwise connected with the proper conducting contacts.

The apparatus shown in Figs. 4-6 operates on the same principle as just described, the only difference in detail being that the tabulating devices controlled by the magnets 70-75 are sorting guides instead of register counters. The sorting guides 100, of which six are shown, control the passage of the record-card to seven different compartments. The seventh or right hand compartment receives the defective records. Each of the other compartments may be assumed to correspond with one of the counters, that is to say the second compartment from the left is arranged to receive the records of native, white females, and so on. The guides are made of flexible material such as spring metal or may be pivoted at their lower ends. The left hand guide is connected with a reciprocating actuating bar 101, and each of

the remaining guides is connected with one of the other bars 102—106, by means of ears 107 which are formed on each bar and which receive and hold the edge of its guide or a projection thereon. A spring 108 secured to each guide tends to carry the guides to the left and a rock-arm 109 is carried back and forth at each operation of the machine by a cam 110 which is driven by the motor 11 in 5 synchronism with the feeding devices. The rock-arm 109 engages the ends of the bars 101—106 and, except when latched, as hereinafter described, the guides will be reciprocated across the path of movement of the 10 descending card at each revolution of the cam 110. The armature of each of the magnets 70—75 is provided with a latch, one of which is mounted at the side of each of the bars 101—106. These latches are designated 15 by the numbers 111—116. Each of the bars 101—106 is provided with a notch 118 which, when the bars and guides are held to the right, lies just under the point of its latch. If now the record, punched as shown in Fig. 20 25 3, be fed under the brushes, the contacts in series with the magnet 71 will all be closed and when the circuit 41 is closed by the cam 85, the magnet 71 will be energized attracting its armature and throwing the latch 112 into the notch on the bar 102. The revolution of the cam 110 will then permit the bar 101 and the guide which it controls to move 30 toward the left under the action of its spring 108, but the bar 102 and its guide and 35 all the guides behind it will be held from movement by the latch 112. A space will thus be opened between the first and second guides and the descending card will pass between them into the compartment representing 40 native, white females. After this occurs the cam 110 in its continued revolution will carry the bar 101 and its guide back to their initial position ready for another operation. If by reason of a defective record or if for 45 any reason a circuit is not closed through any of the magnets the guides will all move to the left and the record will enter the compartment at the right.

In the operation of my system of tabulation, the items on each record should generally bear some well defined relation to each other. That is to say, if one item on the record represents a certain condition, or 50 value or amount, other items would probably or necessarily fall within certain expected and determinable limits, as for instance, in shop cost accounting a given number of hours' work would necessarily imply that wages for the work would be neither 55 above nor below a certain amount. In agricultural statistics, to cite another example, the probable maximum and minimum limits of quantity and value could be readily determined from the number of acres under 60 cultivation, and in the compilation of freight

statistics there would exist the same necessary or expected relation between items representing commodity, weight, distance and carrying charges, and if any record does not present a necessary or usual collocation of 70 items, it indicates the existence of an error in the compilation or transcription of the data, and requires an examination of the record, and a comparison with the original data, for verification or rejection. 75

In Figs. 8 and 9, I have illustrated a simple arrangement of apparatus and circuits for use in the verification of the records, by which the existence of any such abnormal records, containing inconsistent or impossible characteristics or items, are rejected or 80 separately grouped so that they may be readily examined and if necessary, compared with the original data.

For the purpose of facilitating the description of this form of apparatus and its mode of operation I assume that in a given scheme of tabulation, the records either before or after tabulation, have been sorted or 85 classified into groups, one of which represents some condition or occupation in which it would be impossible or unusual that any individual in the group should be a male, or should be less than 15 or more than 59 years of age. The presence in the group, of a record 90 denoting a male or denoting an age outside of the limits mentioned, would presumptively indicate the existence of an error, requiring its separation from the other records of the group, and the apparatus is 95 arranged to accomplish this result.

The index-point positions denoting age are located in the second or middle column of the record, the third position from the bottom representing ages less than 5 years, 100 the fourth position representing ages of 5 or over but under 15 years and so on as indicated in Fig. 3. The bottom position m , represents males, and the second position f , represents females as previously explained. 105 The commutator section 19, to which current is carried by the conducting brush 7 (Fig. 1) is partly shown in Fig. 8. Each of the conducting contacts 22 is connected with a series-relay magnet and a relay-magnet. As 110 the construction and operation of these magnets have already been described, I have shown only a diagrammatic representation of them in Fig. 8. The series-relay magnets are represented by the numbers 150 to 159; 115 the relay-magnets are indicated by the numbers 160 to 169, and the relay contacts of the magnets 161 and 167 by the numbers 170 and 171. The magnets are connected in a circuit 175 and the contacts 161 and 167 are 120 connected in series in a circuit 176, (Fig. 9). For the sake of clearness, I have illustrated these circuits in separate diagrams as heretofore explained in describing the apparatus 125 illustrated in Figs. 1 and 2. 130

The commutator contacts 22 of the commutator section 19 represent, in inverse order, as before explained, the index-point positions of the middle column of the record. 5 That is to say, the top contact represents males, the next one females, the third contact from the top, ages under 5 years and so on. The top contact is by means of suitable conductors and switching devices arranged 10 in circuit with the magnets 150 and 160, but in the diagram these magnets and their contacts are shown disconnected by a switch 180. The second contact is similarly connected with its magnets 151 and 161, but 15 the switch 181 controlling these two magnets is closed. Each set of magnets, comprising a series-relay magnet and a relay-magnet, is similarly arranged in circuit with its commutator contact and the switches 180 to 189, 20 controlling these circuits, are all shown open with the exception of 181 and 187. The fifth, sixth, seventh and eighth commutator contacts, which collectively represent all ages from 15 to 59 years, are all connected 25 with the coils of the magnets 157, 167, by means of the switch 187 and conductor 190.

For the purpose of clearly showing that the circuits may be variably arranged and connected, to adapt the apparatus for any 30 plan or scheme of verification, I have illustrated and described switches 180 to 189 in the circuits to the relay magnets. But it will of course be understood that in actual practice, these switches may be omitted and the 35 electrical connection of the proper magnets effected by direct connections or conductors, the other magnets or contacts being entirely disconnected.

An independent circuit-controlling device, comprising contacts 191, is arranged in 40 the circuit 176 controlled by the relay-contacts, and the cam 192 actuated by the motor 11 is employed to momentarily close the contacts 191 after the relay-contacts 170 and 171 45 close, and before the circuit 175 is broken by the cam 178. The closing of this circuit energizes a magnet, 193, controlling the operation of the tabulating device, which in this particular form of the invention is a 50 pivoted deflector 194 actuated to guide the card into either of the compartments 195 or 196, according to the position of the deflector. The deflector 194 is normally held in the position shown in Fig. 9 by the armature 197 and latch lever 198, but if a record 55 having an index-point at the position *f*, and at any of the positions representing ages from 5 to 59 years be fed through the machine the contacts 170 and 171 in the circuit 60 176 will be closed, and will be held closed by the action of the series-relay magnets 151, 157, until the circuit 176 is closed by the contacts 191 and cam 192. The closing of the circuit will energize the magnet 193 and 65 its armature will be moved to release the le-

ver 198 and deflector 194 which, under the action of the spring 199 will be moved into the position shown in dotted lines and the record will be guided into the compartment 195. The circuit 175 will then be broken by 70 the cam 178, and the relay-contacts 170 and 171 will open, the armature 197 will be released and the cam 200 will reset the latch lever and the deflector. If however, the age index-point be in a position representing an 75 age either above or below the predetermined limits, or if the position representing females be not punched, the record will not close both of the relay-contacts 170 and 171, the circuit 176 will remain open, the magnet 80 will not operate to release the deflector and the record will be guided into the compartment 196. At the conclusion of a run, the abnormal records will all be separated from the normal records and grouped in the compartment 196, whence they can be removed 85 and verified or corrected.

Other arrangements of circuits and apparatus will readily suggest themselves to those skilled in the art and other suitable forms of 90 switch devices or circuit connectors may be employed to effect the desired connections between the circuit controlling device controlled by the record and the actuating magnet or magnets.

I have in referring to the fact that many modifications may be made in the arrangement of circuits and connections also stated that mechanically operating devices may be substituted for the relay magnets illustrated, 100 and in Fig. 7 I show one form of such mechanically acting devices. In this construction the armatures 130 of the magnets 131 serve as latches to hold spring actuated contacts 132 out of contact with their opposing 105 members. When a circuit is completed through the coils of any of the magnets its armature releases a contact 132 which contacts with its opposing member and closes a circuit through the relay magnet coils 136, 110 holding it closed while the card passes under the brushes and until the cam 133 actuates the resetting bar 134 to relatch the contact 132, by means of studs 135 on the resetting bar which engage the contact 132 and carry 115 it back into engagement with its armature as the bar 134 is reciprocated.

The particular apparatus which I have shown and described as a typical embodiment of my invention is arranged to operate 120 on open circuits, but it will of course be understood that the invention is not necessarily restricted to the employment of normally open circuits although for obvious reasons I prefer that arrangement.

I claim:

1. In a system such as described, the combination of a tabulating device, a magnet which controls its operation, a plurality of contacts in circuit with said magnet, a rec- 130

ord having index-point positions arranged in column, the different positions of a column representing different characteristics, a record controlled circuit controlling 5 device which is common to the index-point positions of a column and means, including said circuit controlling device for actuating each contact in said magnet circuit according to the location of the index-point in its 10 column, to permit the actuation of said tabulating device when the contacts controlling the same have been actuated.

2. In a system such as described, the combination of a tabulating device, a magnet 15 which controls its operation, a plurality of contacts in circuit with said magnet, a record-card having index-point positions arranged in columns, a circuit controlling device which is common to the index-point positions of a column and means, including said circuit controlling device for actuating each contact in said magnet circuit according to the location of the index-point in its 20 column, and means independent of said circuit controlling device for controlling the circuit through said contacts in the magnet circuit.

3. In a system such as described, the combination of a tabulating device, a magnet 30 which controls its operation, a plurality of contacts in circuit with said magnet, a record-card having index-point positions arranged in column, the different positions of a column representing different characteristics, a record-controlled circuit controlling device which is common to the index-point positions of a column, means for presenting the index-point positions of a column successively to said circuit controlling device, 35 and means, including said circuit controlling device for actuating each contact in said magnet circuit according to the location of the index-point in its column, to permit the actuation of said tabulating device 40 when the contacts controlling the same have been actuated.

4. In a system such as described, the combination of a tabulating device, a magnet 50 which controls its operation, a plurality of contacts in circuit with said magnet, a record-card having index-point positions arranged in columns, a circuit controlling device which is common to the index-point positions of a column, means for presenting the index-point positions of a column successively to said circuit controlling device, means, including said circuit controlling device for actuating each contact in said magnet circuit according to the location of the 55 index-point in its column, and means independent of said circuit controlling device for controlling the magnet circuit through said contacts.

5. In a system such as described, the combination of a tabulating device, a magnet 60

which controls the operation of said device, a plurality of contacts in said magnet circuit, a relay magnet for operating each of said contacts, a record having index-point positions arranged in column the different 70 positions of a column representing different characteristics, a record-controlled circuit controlling device which is common to all the index-point positions of a column, means for presenting the index-point positions of a column successively to said circuit controlling device, and means for successively connecting the relay magnets with said circuit controlling device.

6. In a system such as described, the combination of a tabulating device, a magnet 80 which controls the operation of said device, a plurality of contacts in said magnet circuit, a relay magnet for operating each of said contacts, a record-card having index- 85 point positions arranged in columns, a circuit controlling device which is common to all the index-point positions of a column, means for presenting the index-point positions of a column successively to said circuit controlling device, means for successively connecting the relay magnets with said circuit controlling device, and means, independent of said circuit controlling device, for controlling the circuit through said contacts.

7. In a system such as described, the combination of a tabulating device, a magnet 95 which controls the operation of said device, a plurality of contacts in said magnet circuit, a relay magnet for operating each of said contacts, a record having index-point positions arranged in column, the different positions of a column representing different characteristics, a circuit controlling device 100 which is common to all the index-point positions of a column; means for presenting the index-point positions of a column successively to said circuit controlling device, a plurality of contacts each representing an 105 index-point position of a column, connections between each of said contacts and a relay magnet, and means for connecting said circuit controlling device with each of said last mentioned contacts successively.

8. In a system such as described, the combination of a tabulating device, a magnet 115 which controls the operation of said device, a plurality of contacts in said magnet circuit, a relay magnet for operating each of 120 said contacts, a record-card having index-point positions arranged in columns, a circuit controlling device which is common to all the index-point positions of a column, means for presenting the index-point positions of a column successively to said circuit controlling device, a plurality of contacts one for each index-point position of a column, connections between each of said contacts 125 and a relay magnet, means for connecting 130

said circuit controlling device with each of said last mentioned contacts successively, and means, independent of said circuit controlling device for controlling the circuit 5 through the relay contacts.

9. In a system such as described, the combination of a tabulating device, a magnet which controls its operation, a plurality of contacts in circuit with said magnet, a record 10 having index-point positions arranged in column, the different positions of a column representing different characteristics, a circuit controlling device which is common to the index-point positions of a column, a relay magnet for operating each of 15 said contacts, and means intermediate the circuit controlling device and relay magnet for controlling the operation of the latter according to the position of the index-point 20 in its column.

10. In a system such as described, the combination of a tabulating device, a magnet which controls its operation, a plurality of contacts in circuit with said magnet, a record 25 having index-point positions arranged in column, the different positions of a column representing different characteristics, a circuit controlling device which is common to the index-point positions of a column, means for presenting the index-point 30 positions of a column successively to said circuit controlling device, means, including said circuit controlling device for actuating each contact in said magnet circuit according 35 to the location of the index-point in its column, a relay magnet for operating said contacts, and means intermediate the circuit controlling device and the relay magnet for controlling the operation of the latter according 40 to a predetermined position of the record-card and said circuit controlling device.

11. In a system such as described, the combination of a tabulating device, a magnet 45 which controls its operation, a plurality of contacts in circuit with said magnet, a record-card having index-point positions arranged in columns, a circuit controlling device which is common to the index-point positions of a column, means for presenting the index-point 50 positions of a column successively to said circuit controlling device, means, including said circuit controlling device for actuating each contact in said magnet circuit according to the location of the index-point in its column, a relay magnet for operating said contacts, means intermediate the circuit controlling device and the relay magnet for controlling the operation 55 of the latter according to a predetermined position of the record-card and said circuit controlling device, and means independent of said circuit controlling device for controlling the circuit through the relay contacts.

12. In a system such as described, the combination with a tabulating device, of a magnet for operating the same, a record-card having index-points, a plurality of circuit closing means in the magnet circuit and 70 means for connecting said circuit closing means whereby the closing of a circuit by any one of a plurality of index-points within predetermined limits will actuate said magnet.

13. In a system such as described, the combination of a tabulating device, a magnet which controls its operation, a plurality of contacts in said magnet circuit, a record-card having index-points, and means, including switch devices or connections, and a circuit controlled by the index-points, for effecting the actuation or control of a single contact by any one of a predetermined number of index-points.

14. In a system such as described, the combination of a tabulating device, a magnet which controls the operation of said device, a plurality of contacts in said magnet circuit, a relay magnet for operating each of 90 said contacts, a record-card having index-point positions arranged in columns, a circuit controlling device which is common to the index-point positions of a column, and connections by which a single relay contact 95 is actuated by an index-point located in any one of a plurality of predetermined index-point positions.

15. In a system such as described, the combination of a tabulating device, a magnet which controls the operation of said device, a plurality of contacts in said magnet circuit, a relay magnet for operating each of 100 said contacts, a record-card having index-point positions arranged in columns, a circuit controlling device which is common to the index-point positions of a column, connections by which a single relay contact is 105 actuated by an index-point located in any one of a plurality of predetermined index-point positions, and means independent of said circuit controlling device for controlling the circuit through the relay contacts.

16. In a system such as described, the combination of a tabulating device, a magnet which controls its operation, a plurality of contacts in circuit with said magnet, a record-card having index-point positions each 115 representing a different characteristic or condition arranged in columns, a circuit controlling device common to the index-point positions of a column, means for feeding the record-card to present the index-point positions of a column successively to the circuit controlling device, means for closing each of 120 said contacts at a predetermined point in the movement of the record, means for holding the contacts closed for a variable period, the length of which is determined by the location of the index-point, means for actuat- 125 130

ing the magnet which operates the tabulating device, and means for opening said contacts.

17. In a system such as described, the combination of a tabulating device, a magnet which controls its operation, a plurality of contacts each representing a different characteristic or condition in circuit with said magnet, a record-card, a circuit controlling device for establishing the control of said contacts, means independent of the circuit controlling device for maintaining such control, and means for releasing such control.

18. In a system such as described, the combination of a tabulating device, a magnet which controls its operation, a plurality of contacts each representing a different characteristic or condition in circuit with said magnet, a record-card, a circuit controlling device for establishing the control of said contacts, means independent of the circuit controlling device for maintaining such control, means for actuating said magnet, and means for releasing the control of said contacts.

19. In a system such as described, the combination of counters and circuits, a plurality of contacts in each counter circuit, each contact representing a different characteristic of the unit or item, a record-card provided with index-point positions representing different characteristics, circuit controlling devices common to a plurality of index-point positions, means controlled by the circuit controlling device for actuating the contacts in the counter circuits, and means controlled by said contacts for actuating the counters.

20. In a system such as described, the combination of counters for separately registering units according to their characteristics, a plurality of contacts, each representing a characteristic of the unit, in each counter circuit, a record-card having an index-point position for each characteristic arranged in column, the different positions of a column representing different characteristics, a record controlled device controllable by an index-point formed in any position of a column, means for presenting the index-point positions of a column successively to said record controlled device, means for actuating said contacts in accordance with the location of an index-point, and means controlled by said contacts for actuating the counters.

21. In a system such as described, the combination of counters for separately registering units according to their characteristics, a plurality of contacts, each representing a characteristic of the unit, in each counter circuit, a record-card having an index-point position for each characteristic arranged in columns, a record controlled device controllable by an index-point formed

in any position of a column, means for presenting the index-point positions of a column successively to said record controlled device, means for actuating said contacts in accordance with the location of an index-point and means independent of the record controlled device for closing the counter circuits through the relays.

22. In a system such as described the combination of a tabulating device, a magnet which controls the operation of said device, a plurality of contacts in circuit with said magnet, a relay-magnet for operating each of said contacts, a record-card having index-point positions, a circuit controlling device actuated by an index-point on the record, and connections between the relay magnets and the circuit controlling device, by which a single relay-contact is actuated by an index-point in any of a plurality of predetermined index-point positions having different characteristics.

23. In a system such as described, the combination of a tabulating device, a magnet which controls its operation, a plurality of contacts in circuit with said magnet, a record-card having index-points, a circuit controlling device which is rendered operative by the index-points to actuate said contacts, and means independent of said circuit controlling device for closing a circuit through said contacts.

24. In a system such as described, the combination of a tabulating device, a magnet which controls its operation, a plurality of contacts, each representing a different characteristic, in circuit with said magnet, a record-card having index-points, a circuit controlling device rendered operative by the index-points to actuate the contacts represented by the index-points and a second circuit controlling device free from the control of the record-card for closing a circuit through said contacts to operate said magnet.

25. In a system such as described, the combination with a tabulating device and an operating magnet, a plurality of contacts in circuit with said magnet, actuating means for establishing the control of said contacts, and means for maintaining such control after they are free from the control of the actuating means.

26. In a system such as described, the combination with a tabulating device and an operating magnet, a plurality of relay contacts in circuit with said magnet, means for actuating the relay magnets, and means for maintaining a circuit through said magnets after they are free from the control of the actuating means.

27. In a system such as described, the combination with a tabulating device and an operating magnet therefor, of a plurality of contacts in said magnet circuit, actuating

means for said contacts and a series relay magnet for operating said actuating means, means for operating said series relay magnet, and means independent of said operating means for maintaining the control of the series relay magnet.

28. In a system such as described, the combination with a tabulating device, and an operating magnet, of a plurality of contacts in said magnet circuit, a relay magnet for operating each of said contacts, a series relay magnet in circuit with each of said relay magnets, and means for closing a circuit through said series relay magnets to 10 actuate the same and close a circuit independent of the actuating circuit.

29. In a system such as described the combination of a tabulating device means for operating the same an electric circuit which 20 controls said operating means, a plurality of contacts in said circuit, record feeding means, a motor for operating the same, a circuit controlling device actuated by said motor for controlling the circuit through 25 said contacts and a record-controlled circuit controlling device for actuating said contacts.

30. In a system such as described the combination of counters and counter circuits, 30 a plurality of contacts, each representing a different characteristic of the unit or item, in each counter circuit, a record-card provided with index-point positions each representing one of said characteristics, circuit- 35 controlling devices each of which is common to a plurality of said index-point posi-

tions and which are actuated by the index-points, means controlled by the circuit-controlling devices for actuating the contacts in the counter circuits, means controlled by 40 said contacts for actuating the counters, a plurality of record receiving compartments, means, also controlled by said contacts, for determining which compartment shall receive the record and means for delivering 45 the record to such compartment.

31. In apparatus of the character described, the combination of a record card, a contact device controlled thereby and forming a terminal for an electric circuit, 50 and a rotating contact member forming an opposite terminal for the circuit.

32. In apparatus of the character described, the combination of a record card, a contact device controlled thereby, and forming a terminal for an electric circuit, a rotating contact member forming an opposite terminal for the circuit and means, comprising feed rollers, for feeding the card 55 between said terminals.

33. In apparatus of the character described, the combination with a record card, of a contact device controlled thereby, a rotating conducting member and rotating feeding means coöperating with said rotating conducting member to feed the cards 60 between the latter and the record-controlled contact device.

HERMAN HOLLERITH.
